ELEUTHERE PAUL DUPONT, OF MONTCHANIN, DELAWARE

MEANS FOR LUBRICATING INTERNAL COMBUSTION ENGINES

Application filed May 24, 1927. Serial No. 193,769.

My invention relates to means for lubricating internal combustion engines and more particularly to means for affording a supply of lubricant to the cylinders of an engine 5 on starting.

As is well known, when an internal combustion engine is idle for a time, the lubricating oil drains away from the cylinders, so that when the engine is started the cylinders are without lubrication until the oiling system with which the engine is provided has had time to supply lubricant to the cylinders. In cold weather when the lubricating oil thickens and in engines of the type in 15 which the cylinders are lubricated by oil escaping from the connecting rod bearings, to which it is supplied through a passage formed in the crank shaft, a very substantial period of time elapses between the starting 20 of the engine and the effective supply of oil to the cylinder walls. During such period of time the cylinder walls are without effective lubrication, with the result that the cylinder walls and pistons are subjected to 25 excessive wear and frequently more positively damaged.

Now, it is the object of my invention to provide means for effectively lubricating the cylinders on starting and until the main lubricating system of the engine becomes effective for their lubrication.

Having now indicated, in a general way, the nature and purpose of my invention, I will proceed to a detailed description thereof 35 with reference to the accompanying drawing in which there is illustrated a preferred embodiment and in which:—

The figure is a sectional view of an engine embodying my invention.

40 In the drawing *a* indicates a cylinder provided with an intake valve *b* and an exhaust valve *c*, which control suitable intake and exhaust passages. Within the cylinder is a piston *d* connected by means of a rod *e* with a crank shaft *f* suitably mounted in a crank case *g*.

45 The engine illustrated, which is of the multi-cylinder type, is provided with any usual type of oiling system and a sump *h* is provided beneath the crank case to hold a

supply of lubricating oil. Within the sump *h* is positioned a cylinder *i* within which is a piston *j* adapted to be operated against the action of a spring *k*. A lip *l* is formed on the upper end of the cylinder *i* to enable oil to 55 enter the cylinder beneath the piston *j* when it is in raised position.

The cylinder *i* is connected at its lower end by means of a pipe *m* with a header *n*, which extends lengthwise of the engine. Above the header *n* and opposite to each of the cylinders of the engine is positioned a chamber *o*. The several chambers are each connected to the header *n* by means of a pipe *p* entering the chamber at its lower end and equipped with 60 a check valve *q*, and each chamber is connected at a point near its lower end to the interior of a cylinder by means of a pipe *r*.

The piston *j* in the cylinder *i* is connected by means of a rod *s* to an arm *t* extending 65 from the casing of the engine starting motor *v*. The starting motor *v* is mounted so as to be rotatable through part of a revolution when it is energized for starting the engine.

The operation of the device above 70 described will be clear when it is noted that when it is started the starting motor will be revolved in the direction of the arrow by reaction when it initially attempts to turn over the engine. The revolution of the starting 75 motor will be stopped and the motor made rigid when the arm contacts with the crank case.

The revolving of the starting motor causes 80 the piston *j* in the cylinder *i* to be depressed causing oil, which has flowed in and filled the cylinder since the last operation of the piston, to be forced into header and from thence into the chambers *o*. As oil is forced 85 into the chambers *o*, it compresses air in the top of the chambers and when the piston *j* is fully depressed the check valves *q* prevent return of the oil to the header. The oil in chambers *o* is then forced by the compressed 90 air into the cylinders and since a substantial quantity of oil is provided to each of the chambers the flow to the cylinders continues 95 for an appreciable time as the engine is started, effectively lubricating the cylinders 100

until the lubricating system of the engine becomes effective to lubricate them.

It will be noted that since the oil is supplied to chambers *o*, from which it flows to the cylinders under the influence of compressed air, as a result of a turning movement of the starting motor casing due to reaction from the engine which it seeks to turn over, no manual effort is necessary to lift the oil to chambers *o*; and it will be further noted that oil is supplied to and begins to flow to the cylinders from the chambers *o* at the time when the engine is initially turned over by the starting motor. The flow of oil to the cylinders is, it will be noted, positively effected under the influence of the air compressed in the chambers by the oil forced therein by the piston *j*.

When the chambers *o* are emptied, lubrication from that source ceases until the engine is stopped and again started.

Having now fully described my invention, what I claim and desire to protect by Letters Patent is:—

- 26 1. Means for lubricating an engine on starting, which includes in combination, a starting motor, an oil pump, means affording a conduit for the passage of oil from the pump to a cylinder of the engine and means 30 affording an operative connection between the starting motor and pump, the starting motor being so mounted as to turn bodily when initially energized to effect operation of the pump.
- 35 2. Means for lubricating an engine on starting, which includes in combination, a starting motor, in driving relation with the engine, an oil pump, means affording a conduit for the passage of oil from the pump to a 40 cylinder of the engine and means affording an operative connection between the starting motor and the pump, the starting motor being revolutely mounted and adapted to be bodily rotated by reaction on being initially 45 energized and to thereby effect operation of the pump before driving the engine.

3. Means for lubricating an engine on starting, which includes in combination, a starting motor, an oil pump, a chamber, conduits for the passage of oil from the pump to the chamber and from the chamber to a cylinder of the engine, and means affording a connection between the starting motor and the pump, the starting motor being so mounted as to turn bodily when initially energized to effect operation of the pump.

4. Means for lubricating an engine on starting, which includes in combination, a starting motor, an oil pump, a chamber, conduits for the passage of oil from the pump to the chamber and from the chamber to a cylinder of the engine, a check valve adapted to prevent the return of oil from said chamber to the pump and means affording 65 a connection between the starting motor and

the pump, the starting motor being so mounted as to turn bodily when initially energized to effect operation of the pump.

5. Means for lubricating an engine on starting, which comprises in combination, a starting motor in driving relation with the engine, an oil pump, a series of chambers corresponding in number to the number of cylinders of the engine, a header, a conduit for the passage of oil from the oil pump to the header, conduits affording passages for oil from the header to said chambers, check valves controlling said conduits, conduits affording passages for oil from each of said chambers to the cylinders of the engine respectively and means affording an operative connection between the starting motor and the oil pump, the starting motor being revolutely mounted and adapted on being initially energized to bodily rotate to actuate the oil pump before driving the engine.

6. In combination with an engine cylinder having a reciprocating piston therein, lubricating means for said cylinder comprising a chamber, a conduit joining said chamber and cylinder and entering a portion of the cylinder wall covered by the piston during a portion of its stroke, and a second conduit communicating with said chamber, said chamber being closed above the points of communication of the conduits to form an air dome, whereby, when lubricant is forced into said chamber through said second conduit, air is compressed in said chamber, the expansion of which air causes lubricant to flow through the first mentioned conduit into said cylinder.

7. In combination with an engine cylinder having a reciprocating piston therein, lubricating means for said cylinder comprising a chamber, a conduit joining said chamber and cylinder and entering a portion of the cylinder wall covered by the piston during a portion of its stroke, a second conduit communicating with said chamber and means for preventing flow of lubricant from said chamber into said second conduit while permitting flow of lubricant from said second conduit into said chamber, said chamber being closed above the points of communication of the conduits to form an air dome, whereby, when lubricant is forced into said chamber through said second conduit, air is compressed in said chamber, the expansion of which air causes lubricant to flow through the first mentioned conduit into said cylinder.

8. In combination with a series of engine cylinders having reciprocating pistons therein, lubricating means comprising a chamber for each cylinder, a conduit joining each chamber with its corresponding cylinder and entering a portion of the cylinder wall covered by the piston during a portion of its stroke, and a header communicating with all

of the chambers, each of the chambers being closed above the points of communication with the header and its conduit to form an air dome whereby, when lubricant is forced 5 into said chambers from said header, air is compressed in said chambers, the expansion of which air causes lubricant to flow from the chambers into the cylinders.

9. In combination with a series of engine 10 cylinders having reciprocating pistons therein, lubricating means comprising a chamber for each cylinder, a conduit joining each chamber with its corresponding cylinder and entering a portion of the cylinder wall cov- 15 ered by the piston during a portion of its stroke, a header communicating with all of the chambers, and means preventing the flow of lubricant from the chambers into the header while permitting flow of lubricant 20 from the header into the chambers, each of the chambers being closed above the points of communication with the header and its conduit to form an air dome whereby, when lubricant is forced into the chambers from 25 said header, air is compressed in said chambers, the expansion of which air causes lubricant to flow from the chambers into the cylinders.

10. In combination with an internal com- 30 bustion engine having a cylinder and a piston arranged to reciprocate in the cylinder, starting means for the engine, means oper- ative automatically upon initiation of oper- ation of the starting means to deliver im- 35 pulsively a quantity of lubricant, a conduit entering a portion of the cylinder wall cov- ered by the piston during a portion of its stroke, and means arranged to receive said impulsively delivered quantity of lubricant 40 and in turn deliver it gradually to the cyl- inder through the conduit.

11. In combination with an internal com- 45 bustion engine having a series of cylinders and pistons arranged to reciprocate therein, starting means for the engine, means oper- ative automatically upon initiation of oper- ation of the starting means to deliver im- 50 pulsively a quantity of lubricant, conduits entering portions of the cylinder walls cov- ered by the pistons during portions of their strokes, and means arranged to receive said impulsively delivered quantity of lubricant and in turn deliver it gradually to the cyl- inders through the conduits.

55 In testimony of which invention, I have hereunto set my hand, at Montchanin, Dela- ware, on this 19th day of May, 1927.

ELEUTHERE PAUL duPONT.
